CLAIM

We claim the ornamental design for an audio control device, as shown and described.

DESCRIPTION

FIG. 1 is a perspective view of an audio control device showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The broken lines in the figures represent portions of the audio control device that form no part of the claimed design. The HyperX logo shown in the drawings is a registered trademark of Kingston Technology Corporation.
